ANSON GROVES RONAN, OF TORONTO, CANADA.

RAW-LIQUID-FUEL MEASURER FOR EXPLOSIVE-ENGINES.

SPECIFICATION forming part of Letters Patent No. 752,181, dated February 16, 1904.

Application filed July 22, 1902. Serial No. 116,559. (No model.)

To all whom it may concern:

Be it known that I, ANSON GROVES RONAN, machinist, a subject of the King of Great Britain, residing at Toronto, in the county of York, Province of Ontario, Canada, have invented certain new and useful Improvements in Raw-Liquid-Fuel Measurers for Explosion-Engines, of which the following is a specification.

My invention relates to improvements in raw-liquid-fuel measurers; and the objects of my invention are, first, to combine with an explosion-chamber provided with the usual exhaust-port and igniter and constructed with a separate opening for air and a separate opening for fuel a raw-liquid-fuel-measuring device, (operated by the suction and compression strokes of the piston-head,) by means of which a charge of fuel is measured and fed to the explosion-chamber during portion only of the suction-stroke, so that said charge may be vaporized and mixed with the air in said explosion-chamber during the rest of the suction-stroke and the whole of the compression-stroke, and, secondly, to design a simple and cheap device to supersede carbureters, mixers, and vaporizers of all types; and it consists, essentially, of a conduit designed to be filled with liquid fuel, a valve-stem held in said conduit, a valve-head on one end of said valve-stem, and a valve-head on the other end of said valve-stem, the said conduit opening into said explosion-chamber through said fuel-opening and leading from a suitable source of fuel-supply, as hereinafter more particularly explained.

Figure 1 is a front elevation of my fuel-measurer, and Fig. 2 is a rear elevation of same. Fig. 3 is a horizontal cross-section on the line *a b*, Fig. 1, showing the construction of my device. This figure also shows an explosion-chamber provided with two distinct passage-ways, one for the fuel (to which the measurer is connected) and another for the air. This figure further shows any suitable fuel-reservoir for the measurer. Fig. 4 is a horizontal cross-section through an alternative form of my measurer.

In the drawings like letters of reference indicate corresponding parts in each figure.

50 The body A, together with the cups B' and

B², screwing into said body on each side of same, forms what I call the "casing" of the fuel-measurer. It will be seen from Fig. 3 that the body A is so constructed as to receive the said cups, and as the said cups are hollow thus provide two chambers C and D within said casing. E is a passage-way within the body A, connecting the said chambers together. Within this passage-way E and having longitudinal movement therein is held a valve F, a valve-head G of which is held upon a seat H by a spring I, held between said valve-head and the cup B'. In order to securely hold the spring I in position and alignment with the longitudinal axis of a valve F, I provide a pocket J, (shown by dotted lines in valve-head G,) in which one end of this spring is held, and a hollow screw K, screwing from the outside into the cup B', which contains the other end of the spring. By means of the screw K it will be seen that I can easily adjust the tension of the spring I against the valve F. In order to protect the screw K, I incase same within a housing L, constructed with a chamber M, which will be of sufficient height as not to abut the head of the screw K when said housing is screwed home.

On the shank N of the valve F is screwed a valve-head O. In order to operate this valve-head so as to regulate distance of movement of same from its seat P, (thus regulating the quantity of fuel required for a charge to correspond to the horse-power of the engine,) I provide the following means, but wish to be distinctly understood that I do not confine myself to these means: In valve-head O, I construct a slot q, in which operates a lug R, secured to or forming part of the flared head S of the pin T, (shown dotted.) This head has movement upon the correspondingly-shaped seat U, formed on the inner side of the cup B². Keyed in any suitable way to the pin T is an arm V, by means of which the said pin is revolved, thus moving the valve-head O to or from its seat. In order to keep the head S tight upon its seat, I tightly screw between the arm V and the cup B² on the pin T a nut W against said cup, and on the outer end of said pin T, I screw a nut X tightly against said

arm. This is of course a very common means of locking a valve-head against a seat, so that no matter in which direction same may be turned it will not be loosened therefrom.

5 Valve F is constructed in any suitable manner to provide free flow of fuel when not seated through the passage-way E from chamber D to chamber C. In the drawings I have shown a series of grooves Y, constructed in 10 said valve for this purpose.

8 is a duct leading from the chamber C to communicate with the passage-way in the conduit 9, which leads to the explosion-chamber 10. The conduit 9 is connected to the trunnion 11 by any suitable union-coupling 12. Although I have shown the conduit 9 as opening into the explosion-chamber in a reduced 15 end, I find this is immaterial. I may make the discharge end of said conduit of the same 20 diameter as the rest of the conduit.

13 is the opening through which the fuel is introduced into the explosion-chamber 10, and 14 the opening through which the air is introduced into said explosion-chamber by means 25 of any suitable induction-valve 15 held therein. I do not confine myself to any particular construction of explosion-chamber, except that same must be provided with two separate passage-ways, one for the air and the other for 30 the fuel.

25 is any suitable igniter situated within the explosion-chamber 10. I preferably use an electric igniter.

I shall now describe the operation of my device: The ducts and chambers within the measurer and the conduits leading to and from same are filled with the fuel. We will consider that the measurer and conduits connected therewith are filled and the measurer ready for 35 operation. During the outward movement of the piston-head 16 the pressure within the explosion-chamber 10 is gradually reduced until it is below that of the atmosphere. Consequently the back pressure (if any) against the 40 fuel contained in the conduit 9, duct 8, and chamber C is greatly below that of the atmospheric pressure against the fuel in the grooves Y, chamber D, duct 6, conduit 2, (connected to the said duct by any suitable union-coupling 5 45 screwing over the trunnion 4,) and reservoir 3, into which said conduit opens. Therefore it will be understood that the valve-head G will be moved off its seat H, thus permitting the charge of fuel from the conduit 9 to be fed 50 into the explosion-chamber 10. Simultaneously with this operation the induction-valve 15 is operated so as to permit air to pass into said explosion-chamber. Immediately the piston starts to move inwardly the pressure 55 60 within the explosion-chamber closes the induction-valve 15, and as the end of the conduit 9 opens directly into said explosion-chamber the pressure against fuel in same acts through the passage-ways or ducts before 65 described and forces the valve-head G down

onto its seat H. The spring I of course assists this movement of said valve. As the valve F in the preferred form is provided with two valve-heads, it will be understood that when the valve-head G is being moved away from 70 its seat, as described, the valve-head O is being moved toward its seat R at the same rate of speed and that as soon as the valve-head O seats the passage-way E between the two chambers D and C is closed. This operation 75 prevents the introduction into the explosion-chamber of more fuel than is required, thus always insuring the proper quantity of fuel being delivered thereinto. It will of course be understood that this operation will take place 80 each time energy has to be developed within the explosion-chamber. When the piston-head 16 compresses the charge within the explosion-chamber, it will be understood that the closing of the valve-head G down upon its 85 seat prevents the raw liquid fuel from being forced out of the measurer. It will be seen from this that the valve F is really a check-valve.

By means of a key 18, secured in the body 90 A, operating in a slot 19 in the side of the valve-head G, the valve F is prevented from axial movement.

In order to know the distance the valve-head O is moved to or from its seat to regulate the 95 charge of fuel, I provide the cup B² with a dial B³, provided with suitable marks thereon with which the pointer V', secured to or forming part of the arm V, must be made to register. To decrease the charge of fuel into the 100 chamber C, the arm V must be moved in the direction indicated by arrow, and to increase charge the arm V must of course be moved in opposite direction.

In order to make chambers C and D perfectly tight, I provide annular flanges c and d in same, respectively, around which I place any suitable packing 7, as shown. These said chambers can of course be made tight in any suitable manner, and I do not confine myself 110 to the construction just described. As will be seen, the cups B are jammed against the packing 7 and fit around the outer side of the annular flanges c and d.

The alternative form of my fuel-measurer 115 (shown in Fig. 4) is provided with the ducts 6 and 8 and is connected in any suitable manner to a reservoir and an explosion-chamber, as will be understood. The cups B² and B' are provided with the chambers D and C, which 120 are connected together by the passage-way E. The cup B² in this form is provided with a hollow extension 20, fitting within the passage-way E. Within this extension operates the valve F, which controls the passage of fuel 125 from the chamber D to the chamber C. The modified form of valve is provided for the major portion of its length with a central passage-way F', which communicates with the annular groove F² of said valve by means of a 130

series of small passage-ways F^3 . F^4 is a valve-head, and F^5 seat for same. On the stem F^6 of the valve is held a spring F^7 , which also rests within the cup F^8 of the regulating-spindle F^9 , which is held in the stuffing-box F^{10} , with which the cup B' is provided. By moving in or out the said regulating-spindle the tension of the spring F^7 against the valve F is regulated. When the pressure moves the valve F so as to admit fuel from the chamber D to the chamber C , the stem F^6 abuts the end of the cup F^8 and the valve thus limited in its outward movement. It will be understood from this that the distance of movement of the valve-head F^4 from its seat is regulated by moving either out or in the regulating-spindle F^9 in order to increase or decrease the charges. The cup B' is made leak-proof in any suitable manner. Communicating with the duct 6 is an annular groove 21, over which a washer 22 (made of any suitable material) is suitably held in place, in which are a series of holes 23, by means of which fuel is conveyed from annular groove 21 to annular groove 24, made in inner end of cup B^2 . The annular groove 24 communicates with the chamber D by means of the duct 25. The cup B^2 is screwed tightly against the washer 22, as shown.

30 The operation of both forms of my fuel-measurer is the same. The direction of the flow of fuel is shown by arrows.

It will of course be understood that I may use a water-jacket round my explosion-chamber without departing from the spirit of my invention.

During the whole of the suction-stroke of the piston-head the alternative form of my invention (shown in Fig. 4) will enable the piston-head to draw in the liquid fuel. The measurer and its conduits will be made of sufficient size so as to permit only the required amount for a charge of raw gasoline to be sucked into the explosion-chamber. This will prevent the admission of too much fuel thereto. In the preferred form (shown in Fig. 3) the measurer will permit the piston-head to suck into the explosion-chamber the required amount for a charge of raw gasoline only during portion of the suction-stroke of same, thus permitting the fed gasoline to be vaporized and mixed with air during the balance of the suction-stroke and the whole of the compression-stroke. The alternative form (shown in Fig. 4) does not permit of as thorough mixing of the air and gasoline; but yet I get most excellent results from same.

I do not confine myself to using an adjustable valve, but preferably use one.

60 I have minutely described and shown the construction and parts of my preferred form, together with a modification of same, of my fuel-measurer; but it must be distinctly understood that I do not confine myself to any particular construction of fuel-measurer that will

perform the same function in the same manner that mine does.

Although I preferably use a spring, I may dispense with one in connection with the valve F when same is used in a vertical position.

70 What I claim as my invention is—

1. The combination with the explosion-chamber, of a gas-engine, provided with a distinct air passage-way, and a distinct fuel-opening, and piston-head operating in said explosion-chamber, of a raw-liquid-fuel-measuring device comprising a conduit designed to be filled with liquid fuel and connected to said explosion-chamber by means of its fuel-opening; a valve-stem held in said conduit; a 75 valve-head on one end of said valve-stem, and a valve-head on the other end of said valve-stem; the said valve-stem and valve-heads being operated by a portion of the suction-stroke of said piston-head to permit same to draw a charge of raw liquid fuel into said explosion-chamber, one of said valve-heads automatically cutting off the further supply of liquid fuel into said explosion-chamber notwithstanding the continued suction-stroke of 80 said piston-head, and the other valve-head being operated by the compression-stroke of said piston-head to prevent the pressure within the explosion-chamber from forcing the raw liquid fuel out of said conduit.

90 95 2. The combination with the explosion-chamber, of a gas-engine, provided with a distinct air passage-way, and a distinct fuel-opening, and piston-head operating in said explosion-chamber, of a raw-liquid-fuel-measuring device comprising a conduit designed to be filled with liquid fuel and connected to said explosion-chamber by means of its fuel-opening; a valve-stem held in said conduit; a valve-head on one end of said valve-stem, and a valve-head on the other end of said valve-stem, the 100 said valve-stem and valve-heads being operated by a portion of the suction-stroke of said piston-head to permit same to draw a charge of raw liquid fuel into said explosion-chamber, one of said valve-heads automatically cutting off the further supply of liquid fuel into said explosion-chamber notwithstanding the continued suction-stroke of said piston-head, and the other valve-head being operated by the 105 compression-stroke of said piston-head to prevent the pressure within the explosion-chamber from forcing the raw liquid fuel out of said conduit, and a spring combined with said valve-stem.

110 115 120 125 3. The combination with the explosion-chamber, of a gas-engine, provided with a distinct air passage-way, and a distinct fuel-opening, and piston-head operating in said explosion-chamber, of a raw-liquid-fuel-measuring device comprising a conduit designed to be filled with liquid fuel and connected to said explosion-chamber by means of its fuel-opening; a valve-stem held in said conduit; an adjustable valve-head on one end of said valve- 130

- stem; a valve-head on the other end of said valve-stem, the said valve-stem and valve-heads being operated by a portion of the suction-stroke of said piston-head to permit same 5 to draw a charge of raw liquid fuel into said explosion-chamber, one of said valve-heads automatically cutting off the further supply of liquid fuel into said explosion-chamber notwithstanding the continued suction-stroke of 10 said piston-head, and the other valve-head being operated by the compression-stroke of said piston-head to prevent the pressure within the explosion-chamber from forcing the raw liquid fuel out of said conduit.
- 15 4. The combination with the explosion-chamber, of a gas-engine, provided with a distinct air passage-way, and a distinct fuel-opening, and piston-head operating in said explosion-chamber, of a raw-liquid-fuel-measuring 20 device comprising a conduit designed to be filled with liquid fuel and connected to said explosion-chamber by means of its fuel-opening; a valve-stem held in said conduit; an adjustable valve-head on one end of said 25 valve-stem, and a valve-head on the other end of said valve-stem, the said valve-stem and valve-heads being operated by a portion of the suction-stroke of said piston-head to permit same to draw a charge of raw liquid fuel 30 into said explosion-chamber, one of said valve-heads automatically cutting off the further supply of liquid fuel into said explosion-chamber notwithstanding the continued suction-stroke of said piston-head, and the other 35 valve-head being operated by the compression-stroke of said piston-head to prevent the pressure within the explosion-chamber from forcing the raw liquid fuel out of said conduit, and a spring combined with said valve-40 stem.
- 45 5. The combination with the explosion-chamber of a gas-engine provided with a distinct air passage-way, and a distinct fuel-opening, and piston-head operating in said explosion-chamber, of a fuel-measurer comprising a casing provided with a central passage-way and two ducts, two cups each screwing into a side of said casing thus forming two chambers which are connected together by said 50 central passage-way, the said ducts opening into said chambers; a valve-stem held in said central passage-way and constructed so as to permit flow of fuel from one chamber to another; a valve-head on one end of said 55 valve-stem operating in one of said chambers; a valve-head on the other end of said valve-stem operating in said other chamber, the said valve-stem being operated by a portion of the suction-stroke of said piston-head so as 60 to permit said piston-head to draw a charge of raw liquid fuel into said explosion-chamber, one of said valve-heads automatically cutting off the further supply of liquid fuel into said explosion-chamber notwithstanding the continued suction-stroke of said piston-head; the 65

said valve-stem being operated by the compression-stroke of said piston-head so as to seat said other valve-head to prevent the pressure within the explosion-chamber from forcing the raw liquid fuel out of said casing, 70 a spring combined with said valve-stem, and the fuel-reservoir open to the pressure of the atmosphere.

6. The combination with the explosion-chamber of a gas-engine provided with a distinct air passage-way, and a distinct fuel-opening, and piston-head operating in said explosion-chamber, of a fuel-measurer comprising a casing provided with a central passage-way and two ducts, two cups each screwing into a 80 side of said casing thus forming two chambers which are connected together by said central passage-way, the said ducts opening into said chambers; a valve-stem held in said central passage-way and constructed so as to 85 permit flow of fuel from one chamber to another; a valve-head on one end of said valve-stem operating in one of said chambers; an adjustable valve-head on the other end of said valve-stem operating in said other chamber, 90 the said valve-stem being operated by a portion of the suction-stroke of said piston-head so as to permit said piston-head to draw a charge of raw liquid fuel into said explosion-chamber, one of said valve-heads automatically 95 cutting off the further supply of liquid fuel into said explosion-chamber notwithstanding the continued suction-stroke of said piston-head; the said valve-stem being operated by the compression-stroke of said piston-head so as to seat said other valve-head to prevent the pressure within the explosion-chamber from forcing the raw liquid fuel out of said casing, a spring combined with said valve-stem, and the fuel-reservoir open to the 100 pressure of the atmosphere.

7. The combination with the explosion-chamber of a gas-engine provided with a distinct air passage-way, and a distinct fuel-opening, and piston-head operating in said explosion-chamber, of a fuel-measurer comprising a casing provided with a central passage-way and two ducts, two cups each screwing into a side of said casing thus forming two chambers which are connected together by said 110 central passage-way, the said ducts opening into said chambers; a valve-stem held in said central passage-way and constructed so as to permit flow of fuel from one chamber to another; a valve-head on one end of said valve-115 stem operating in one of said chambers; an adjustable valve-head on the other end of said valve-stem operating in said other chamber, the said valve-stem being operated by a portion of the suction-stroke of said piston-head so as to 120 permit said piston-head to draw a charge of raw liquid fuel into said explosion-chamber, one of said valve-heads automatically cutting off the further supply of liquid fuel into said explosion-chamber notwithstanding the continued suction-stroke of said piston-head 125 so as to permit said piston-head to draw a charge of raw liquid fuel into said explosion-chamber, one of said valve-heads automatically cutting off the further supply of liquid fuel into said explosion-chamber notwithstanding the continued suction-stroke of said piston-head 130

standing the continued suction-stroke of said piston-head; the said valve-stem being operated by the compression-stroke of said piston-head so as to seat said other valve-head to prevent the pressure within the explosion-chamber from forcing the raw liquid fuel out of said casing; a spring combined with said valve-stem; a key secured in said casing and held so as to permit only longitudinal movement of said valve-stem and the fuel-reservoir open to the pressure of the atmosphere.

8. The combination with the explosion-chamber of a gas-engine provided with a distinct air passage-way, and a distinct fuel-opening, and piston-head operating in said explosion-chamber, of a fuel-measurer comprising a casing provided with a central passage-way and two ducts, two cups each screwing into a side of said casing thus forming two chambers which are connected together by said central passage-way, the said ducts opening into said chambers; a valve-stem held in said central passage-way and constructed so as to permit flow of fuel from one chamber to another; a fixed valve-head, provided with a pocket, on one end of said valve-stem, operating in one of said chambers; an adjustable valve-head on the other end of said valve-stem operating in said other chamber; the said valve-stem being operated by a portion of the suction-stroke of said piston-head so as to permit said piston-head to draw a charge of raw liquid fuel into said explosion-chamber, one of said valve-heads automatically cutting off the further supply of liquid fuel into said explosion-chamber notwithstanding the continued suction-stroke of said piston-head; the said valve-stem being operated by the compression-stroke of said piston-head so as to seat said other valve-head to prevent the pressure within the explosion-chamber from forcing the raw liquid fuel out of said casing; a spring combined with said valve-stem, and the fuel-reservoir open to the pressure of the atmosphere.

9. The combination with the explosion-chamber of a gas-engine provided with a distinct air passage-way, and a distinct fuel-opening, and piston-head operating in said explosion-chamber, of a fuel-measurer comprising a casing provided with two duct-provided chambers connected together by a passage-way; a valve-stem, held in said passage-way and constructed so as to permit flow of fuel from one chamber to another; a valve-head on one end of said valve-stem operating in one of said chambers; an adjustable valve-head on the other end of said valve-stem operating in said other chamber, the said valve-stem being operated by a portion of the suction-stroke of said piston-head so as to permit said piston-head to draw a charge of liquid fuel into said explosion-chamber, one of said valve-heads automatically cutting off the further supply of liquid fuel into said explosion-chamber notwithstanding the continued suction-stroke of said piston-head; the said valve-stem being operated by the compression-stroke of said piston-head so as to seat said other valve-head to prevent the pressure within the explosion-chamber from forcing the raw liquid fuel out of said casing; a spring combined with said valve-stem, and the fuel-reservoir open to the pressure of the atmosphere.

10. The combination with the explosion-chamber of a gas-engine provided with a distinct air passage-way, and a distinct fuel-opening, and piston-head operating in said explosion-chamber, of a fuel-measurer comprising a casing provided with two duct-provided chambers connected together by a passage-way; a valve-stem, held in said passage-way

and constructed so as to permit flow of fuel from one chamber to another; a valve-head on one end of said valve-stem operating in one of said chambers; a valve-head on the other end of said valve-stem operating in said other chamber, the said valve-stem being operated by a portion of the suction-stroke of said piston-head so as to permit said piston-head to draw a charge of raw liquid fuel into said explosion-chamber, one of said valve-heads automatically cutting off the further supply of liquid fuel into said explosion-chamber notwithstanding the continued suction-stroke of said piston-head; the said valve-stem being operated by the compression-stroke of said piston-head so as to seat said other valve-head to prevent the pressure within the explosion-chamber from forcing the raw liquid fuel out of said casing; a spring combined with said valve-stem, and the fuel-reservoir open to the pressure of the atmosphere.

11. The combination with the explosion-chamber of a gas-engine provided with a distinct air passage-way, and a distinct fuel-opening, and piston-head operating in said explosion-chamber, of a fuel-measurer comprising a casing provided with two duct-provided chambers connected together by a passage-way; a valve-stem, held in said passage-way and constructed so as to permit flow of fuel from one chamber to another; a valve-head on one end of said valve-stem operating in one of said chambers; an adjustable valve-head on the other end of said valve-stem operating in said other chamber, the said valve-stem being operated by a portion of the suction-stroke of said piston-head so as to permit said piston-head to draw a charge of liquid fuel into said explosion-chamber, one of said valve-heads automatically cutting off the further supply of liquid fuel into said explosion-chamber notwithstanding the continued suction-stroke of said piston-head; the said valve-stem being operated by the compression-stroke of said piston-head so as to seat said other valve-head to prevent the pressure within the explosion-chamber from forcing the raw liquid fuel out of said casing; a spring combined with said valve-stem, and the fuel-reservoir open to the pressure of the atmosphere.

12. The combination with the explosion-chamber of a gas-engine provided with a distinct air passage-way, and a distinct fuel-opening, and piston-head operating in said explosion-chamber, of a fuel-measurer comprising a casing provided with two duct-provided chambers connected together by a passage-way; a valve-stem, held in said passage-way and constructed so as to permit flow of fuel from one chamber to another; a valve-head on one end of said valve-stem operating in one of said chambers; an adjustable valve-head on the other end of said valve-stem operating in said other chamber, the said valve-stem being operated by a portion of the suc-

tion-stroke of said piston-head so as to permit said piston-head to draw a charge of raw liquid fuel into said explosion-chamber, one of said valve-heads automatically cutting off the further supply of liquid fuel into said explosion-chamber notwithstanding the continued suction-stroke of said piston-head; the said valve-stem being operated by the compression-stroke of said piston-head so as to seat said other valve-head to prevent the pressure within the explosion-chamber from forcing the raw liquid fuel out of said casing; a spring combined with said valve-stem; a key secured in said casing and held so as to permit only longitudinal movement of said valve-stem, and the fuel-reservoir open to the pressure of the atmosphere.

12. The combination with the explosion-chamber of a gas-engine provided with a distinct air passage-way, and a distinct fuel-opening, and piston-head operating in said explosion-chamber, of a fuel-measurer comprising a casing provided with two duct-provided chambers connected together by a passage-way; a valve-stem, constructed so as to permit flow of fuel from one chamber to another, provided with a threaded end, operating in said passage-way; a fixed valve-head on one end of said valve-stem, operating in one of said chambers, a key secured in said casing and combined with said valve-stem to permit only longitudinal movement of same; an adjustable valve-head, on the threaded end of said valve-stem, operating in said other chamber, said valve-stem being operated by a portion of the suction-stroke of said piston-head so as to permit said piston-head to draw a charge of raw liquid fuel into said explosion-chamber, one of said valve-heads automatically cutting off the further supply of liquid fuel into said explosion-chamber notwithstanding the continued suction-stroke of said piston-head; the said valve-stem being operated by the compression-stroke of said piston-head so as to seat said other valve-head to prevent the pressure within the explosion-chamber from forcing the raw liquid fuel out of said casing; a spring combined with said valve-stem; a pin held in one side of said casing and being associated with said adjustable valve-head so as to move same; a pointer secured to the outer end of said pin and being intended to indicate, by means of any suitable dial, with which said casing is provided, the distance of movement of said adjustable valve-head, and the fuel-reservoir open to the pressure of the atmosphere.

13. A raw-liquid-fuel-measuring device comprising a conduit designed to be filled with liquid fuel; a valve-stem held in said conduit; a valve-head on one end of said valve-stem, and a valve-head on the other end of said valve-stem, said liquid fuel being subjected to different pressures to operate said valve-stem and valve-heads to control passage of said liquid through said conduit.

14. A raw-liquid-fuel-measuring device comprising a conduit designed to be filled with liquid fuel; a valve-stem held in said conduit; a valve-head on one end of said valve-stem, and a valve-head on the other end of said valve-stem, said liquid fuel being subjected to different pressures to operate said valve-stem and valve-heads to control passage of said liquid through said conduit, and a spring combined with said valve-stem.

15. A raw-liquid-fuel-measuring device comprising a conduit designed to be filled with liquid fuel; a valve-stem held in said conduit; an adjustable valve-head on one end of said valve-stem, and a valve-head on the other end of said valve-stem, said liquid fuel being subjected to different pressures to operate said valve-stem and valve-heads to control passage of said liquid through said conduit.

16. A raw-liquid-fuel-measuring device comprising a conduit designed to be filled with liquid fuel; a valve-stem held in said conduit; an adjustable valve-head on one end of said valve-stem, and a valve-head on the other end of said valve-stem, said liquid fuel being subjected to different pressures to operate said valve-stem and valve-heads to control passage of said liquid through said conduit, and a spring combined with said valve-stem.

17. A raw-liquid-fuel-measuring device comprising a casing provided with two chambers connected together by a passage-way; a valve-stem held in said passage-way; a valve-head on one end of said valve-stem operating in one of said chambers; a valve-head on the other end of said valve-stem operating in said other chamber, the said liquid fuel being subjected to different pressures to operate said valve-heads to control passage of said fuel through said casing.

18. A raw-liquid-fuel-measuring device comprising a casing provided with two chambers connected together by a passage-way; a valve-stem held in said passage-way; a valve-head on one end of said valve-stem operating in one of said chambers; a valve-head on the other end of said valve-stem operating in said other chamber, the said liquid fuel being subjected to different pressures to operate said valve-heads to control passage of said fuel through said casing, and a spring combined with said valve-stem.

19. A raw-liquid-fuel-measuring device comprising a casing provided with two duct-provided chambers connected together by a passage-way; a valve-stem, held in said passage-way and constructed so as to permit flow of fuel from one chamber to another; a valve-head on one end of said valve-stem operating in one of said chambers; a valve-head on the other end of said valve-stem operating in said other chamber, the said liquid fuel being subjected to different pressures to operate said valve-heads to control passage of said liquid through said casing.

20. A raw-liquid-fuel-measuring device comprising a casing provided with two ducts; provided chambers connected together by a passage-way; a valve-stem, held in said passage-way and constructed so as to permit flow of fuel from one chamber to another; a valve-head on one end of said valve-stem operating in one of said chambers; a valve-head on the other end of said valve-stem operating in said other chamber, the said liquid fuel being subjected to different pressures to operate said valve-heads to control passage of said liquid through said casing, and a spring combined with said valve-stem.
21. A raw-liquid-fuel-measuring device comprising a casing provided with two ducts; provided chambers connected together by a passage-way; a valve-stem, held in said passage-way and constructed so as to permit flow of fuel from one chamber to another; a valve-head on one end of said valve-stem operating in one of said chambers; an adjustable valve-head on the other end of said valve-stem operating in said other chamber, the said liquid fuel being subjected to different pressures to operate said valve-heads to control passage of said liquid through said casing, and a spring combined with said valve-stem.
22. A raw-liquid-fuel-measuring device comprising a casing provided with two ducts; provided chambers connected together by a passage-way; a valve-stem, held in said passage-way and constructed so as to permit flow of fuel from one chamber to another; a valve-head on one end of said valve-stem operating in one of said chambers; an adjustable valve-head on the other end of said valve-stem operating in said other chamber, the said liquid fuel being subjected to different pressures to operate said valve-heads to control passage of said liquid through said casing; a spring combined with said valve-stem; and a key secured in said casing and held so as to only permit longitudinal movement of said valve-stem.
23. A raw-liquid-fuel-measuring device comprising a casing provided with two ducts; provided chambers connected together by a passage-way; a valve-stem, held in said passage-way and constructed so as to permit flow of fuel from one chamber to another; a valve-head on one end of said valve-stem operating in one of said chambers; an adjustable valve-head on the other end of said valve-stem operating in said other chamber, the said liquid fuel being subjected to different pressures to operate said valve-heads to control passage of said liquid fuel through said casing; a spring combined with said valve-stem; a key secured in said casing and held so as to only permit longitudinal movement of said valve-stem; a pin held in one side of said casing and being associated with said adjustable valve-head so as to move same, and a pointer secured to the outer end of said pin being intended to indicate, by means of any suitable dial, with which

- said casing is provided, the distance of movement of said adjustable valve-head.
24. A raw-liquid-fuel-measuring device comprising a casing provided with a central passage-way and two ducts; two cups, each screwing into a side of said casing thus forming two chambers which are connected together by said central passage-way, the said ducts opening into said chambers; a valve-stem held in said central passage-way and constructed so as to permit flow of fuel from one chamber to another; a valve-head on one end of said valve-stem operating in one of said chambers; a valve-head on the other end of said valve-stem operating in said other chamber, the said liquid fuel being subjected to different pressures to operate said valve-heads to control passage of said fuel through said casing, and a spring combined with said valve-stem.
25. A raw-liquid-fuel-measuring device comprising a casing provided with a central passage-way and two ducts; two cups, each screwing into a side of said casing thus forming two chambers which are connected together by said central passage-way, the said ducts opening into said chambers; a valve-stem held in said central passage-way and constructed so as to permit flow of fuel from one chamber to another; a valve-head on one end of said valve-stem operating in one of said chambers; an adjustable valve-head on the other end of said valve-stem operating in said other chamber, the said liquid fuel being subjected to different pressures to operate said valve-heads to control passage of said fuel through said casing, and a spring combined with said valve-stem.
26. A raw-liquid-fuel-measuring device comprising a casing provided with a central passage-way and two ducts; two cups, each screwing into a side of said casing thus forming two chambers which are connected together by said central passage-way, the said ducts opening into said chambers; a valve-stem held in said central passage-way and constructed so as to permit flow of fuel from one chamber to another; a valve-head on one end of said valve-stem operating in one of said chambers; an adjustable valve-head on the other end of said valve-stem operating in said other chamber, the said liquid fuel being subjected to different pressures to operate said valve-heads to control passage of said fuel through said casing; a key secured in said casing and held so as to permit only longitudinal movement of said valve-stem, and a spring combined with said valve-stem.
27. A raw-liquid-fuel-measuring device comprising a casing provided with a central passage-way and two ducts; two cups, each screwing into a side of said casing thus forming two chambers which are connected together by said central passage-way, the said ducts opening into said chambers; a valve-stem

held in said central passage-way and constructed so as to permit flow of fuel from one chamber to another; a valve-head on one end of said valve-stem operating in one of said chambers; an adjustable valve-head on the other end of said valve-stem operating in said other chamber, the said liquid fuel being subjected to different pressures to operate said valve-heads to control passage of said fuel through said casing; a key secured in said casing and held so as to permit only longitudinal movement of said valve-stem; a spring combined with said valve-stem; a pin held in one side of said casing and being associated with said adjustable valve-head so as to move same, and a pointer secured to the outer end of said pin and being intended to indicate, by means of any suitable dial, with which said casing is provided, the distance of movement of said adjustable valve-head.

28. The combination with a casing provided with two duct-provided chambers connected together by a passage-way, of a valve-stem held in said passage-way and constructed so as to permit flow of fuel from one chamber to another; a valve-head on one end of said valve-stem operating in one of said chambers; a valve-head on the other end of said valve-stem operating in said other chamber; the said valve-heads being seated alternately by the varying pressure of the liquid within said casing to control passage of said liquid through said chambers and ducts, and a spring combined with said valve-stem.

29. The combination with a casing provided with two duct-provided chambers connected together by a passage-way, of a valve-stem held in said passage-way and constructed so as to permit flow of fuel from one chamber to another; a valve-head on one end of said valve-stem operating in one of said chambers; an adjustable valve-head on the other end of said valve-stem operating in said other chamber; the said valve-heads being seated alternately by the varying pressure of the liquid within said casing to control passage of said liquid through said chambers and ducts, and a spring combined with said valve-stem.

30. The combination with a casing provided with two duct-provided chambers connected together by a passage-way, of a valve-stem

held in said passage-way and constructed so as to permit flow of fuel from one chamber to another; a valve-head on one end of said valve-stem operating in one of said chambers; an adjustable valve-head on the other end of said valve-stem operating in said other chamber; the said valve-heads being seated alternately by the varying pressure of the liquid within said casing to control passage of said liquid through said chambers and ducts; a spring combined with said valve-stem; a key combined with said valve-stem so as to permit only longitudinal movement of same, and means for adjusting said adjustable valve-head. 65

31. A raw-liquid-fuel-measuring device comprising a casing provided with a central passage-way and two ducts; two cups, each screwing into a side of said casing thus forming two chambers which are connected together by said central passage-way, the said ducts opening into said chambers; a valve-stem held in said central passage-way and constructed so as to permit flow of fuel from one chamber to another; a valve-head on one end of said valve-stem operating in one of said chambers; an adjustable valve-head on the other end of said valve-stem operating in said other chamber, the said liquid fuel being subjected to different pressures to operate said valve-heads to control passage of said fuel through said casing; a hollow screw held in one side of said casing in line with said valve-stem; a spring supported in said hollow screw and in the pocket in said fixed valve-head; a key secured in said casing and held so as to permit only longitudinal movement of said valve-stem; a pin held in one side of said casing and being associated with said adjustable valve-head so as to move same, and a pointer secured to the outer end of said pin and being intended to indicate, by means of any suitable dial, with which said casing is provided, the distance of movement of said adjustable valve-head. 70 75 80 85 90 95

In testimony whereof I have signed my name to this specification in the presence of two subscribing witnesses.
